UNITED STATES PATENT OFFICE

ALFRED CRAWFORD, OF NEW BRUNSWICK, NEW JERSEY, ASSIGNEE TO CRAWFORD MANUFACTURING COMPANY, OF NEW BRUNSWICK, NEW JERSEY, A CORPORATION OF NEW JERSEY

STOP MOTION FOR KNITTING MACHINES (HOSIERY)

Application filed March 24, 1928. Serial No. 264,406.

My invention relates particularly to stop motions for circular knitting machines, and comprises means adapted to be operated by the thread detecting mechanism of the ordinary stop motions employed in conjunction with this type of knitting machine, which when a thread becoming broken, slack, or otherwise irregular in its run to the needles of the machine, will rotate a stop motion operating rod, and said rod in turn will cause my improved mechanism to shift the driving belt of the knitting machine from the driving pulley to the loose pulley, on the main power shaft of the machine, and simultaneously therewith apply a brake to the driving pulley, to prevent drifting or subsequent operation of the machine until such time as the stop motion has been reset, after the irregularity in the running thread has been properly corrected.

In view of the thread detecting means of the stop motion forming no part of the present invention, such mechanism has been omitted from the accompanying drawings, of which:

Fig. 1 is a side elevation of sufficient of a knitting machine, generally known as a "Banner" machine, to illustrate the operation of my invention when applied thereto; Fig. 2 is an enlarged side elevational view of the operating mechanism illustrated in Fig. 1;

Fig. 3 is a sectional plan view taken on the line 3—3 of Fig. 2;

Fig. 4 is a side elevation of my invention as applied to a "Brinton" machine;

Fig. 5 is an enlarged side elevational view of the operating mechanism shown in Fig. 4;

Fig. 6 is a transverse sectional elevation taken on the line 6—6 of Fig. 5.

Fig. 7 is a transverse sectional elevation taken on line 7—7 of Fig. 5;

Fig. 8 is a side elevation of my invention as applied to a "Wildman" machine;

Fig. 9 is a front elevation of the mechanism shown in Fig. 8, and

Fig. 10 is a perspective view of a portion of the mechanism shown in Figs. 8 and 9.

In Figs. 1 and 3, the main frame of a "Banner" hosiery knitting machine is illus-

trated at 1, in which is rotatably mounted the main drive shaft 2 having a tight high speed driving pulley 3 secured thereto, a low speed drive pulley 4, and a loose pulley 5, of equal diameter with the tight pulley 3, being rotatably mounted on the shaft 2. A belt shifting yoke 6 is rigidly attached to a shift rod 7 which is slidably mounted in the main frame of the machine and is adapted to move the driving belt (not shown) from one to the other of the above mentioned driving pulley wheels, as required. For this purpose a cam 8, which is a standard part of the "Banner" machine as shown and described in the U. S. Letters Patent to Joshua D. Hemphill, No. 933,443, dated September 7, 1909, is rotatably mounted on the frame 1, and engages a lug 9 on the belt-shifter yoke 6. A spring 10 holds the lug 9 in operative contact with the cam 8, and tends to normally maintain the driving belt in position on the high-speed driving pulley 3.

According to the principles of my invention, I mount a casing 11 on the main frame 1 of the machine. A pair of lugs 12, 12 project horizontally from the casing 11 for the pivotal support 13 of a double bell-crank lever 14, one arm 15 of which is adapted to engage the lug 9 of the belt-shifter yoke 6, a second arm 16 being provided with a roller 17 which rides on an angularly disposed or inclined end 18 of a bar 19 horizontally and slidably mounted in the casing 11. A third arm 20 of the double bell-crank lever 14 has one end of a spring 21 attached thereto, the opposite end of the spring being attached at 22 to the casing 11.

The roller 17 of the bell-crank lever 14 normally occupies a position near the peak 23 of the inclined end 18 of the slide bar 19 and thereby maintains the arm 15 of the lever 14 in an inactive position, illustrated in Fig. 3. Upon moving the said slide bar 19 longitudinally the inclined end thereof moves away from the roller 17 permitting the bell-crank lever 14 to turn on its pivot 13 and the arm 15 to engage the lug 9 of the bell shifter 6, thereby moving the belt from the driving pulley 3 to the loose pulley 5. This movement is accomplished by means of the

spring 21 which overcomes the tension of the spring 10, the spring 10 being of lesser strength than the spring 21.

Longitudinal movement of the slide bar 19 in one direction is effected by a compression spring 24, which is confined between the rear end of the casing 11 and a lug 25 on the slide bar 19, and encircles a rod 26 which projects axially through the spring 24 from the casing 11 and through an opening formed in the lug 25. The slide bar 19 is manually moved in an opposite direction by a lever 27 pivoted at 28 to the casing 11 and adapted to engage a pin 29 which extends laterally from the slide bar 19. A second lateral pin 30 extends from the bar 19, and acts as a limit stop for the lever 27. A rod 31 is pivotally attached to the free end of the lever 27, and extends forward to the front of the machine being there provided with a handle 32.

The slide bar 19 is held in its "set" position against the action of the spring 24 by means of a locking lever 33 which is pivoted at 34 to the casing 11 and has a longitudinal slot 35 formed in its body portion. The slot 35 has an offset recess 36 adapted to receive a locking pin 37 which extends laterally from one side of the slide bar 19. The locking lever 33 is provided with a shoulder projection 38 adapted to be engaged and held by a latch 39 which is pivoted at 40 to the casing 11. A spring 41 holds the latch 39 in operative engagement with the locking lever 33.

35 A trip arm or pin 42 extends horizontally from a vertically disposed trip shaft 43 which is rotatably mounted in the casing 11, and is operatively connected by means of a stop motion trip rod 44 to the thread detecting mechanism (not shown) of the stop motion.

40 A brake lever 45 is pivoted at 46 to a lug 47 on the casing 11, and is provided with an eccentrically disposed pivot 48 for a brake shoe 49, intermediate the pivot 46 and the free end of the brake lever 45. The brake shoe 49 is adapted to engage one of the driving pulleys 3 or 4.

45 A brake-applying lever 50 is pivoted at 51 in the casing 11, and is provided at one end 50 with an adjusting screw 52 adapted to engage the free end of the brake lever 45. A spring 53 is stretched between the opposite end of the brake-applying lever 50 and the casing 11. A holding pin 54 on the slide bar 19 holds the brake-applying lever 50 against the action of the spring 53.

55 In operation, when the stop motion trip rod 44 is partially rotated by the operation of the thread detecting mechanism of the stop motion the pin or arm 42 engages the free end of the latch 39, turning it on its pivot and thereby releasing the said latch from the locking lever 33. When released, the locking lever 33 turns on its pivot and the locking pin 37 moves out of the recess 36

into the slot 35 which releases the slide bar 19. The slide bar 19 is immediately moved longitudinally by the spring 24, the locking pin 37 moving freely in the slot 35 of the locking lever 33. Longitudinal movement of the slide bar 19 by its spring 24 causes the inclined or angular end 18 thereof to move away from the roller 17 on the bell-crank lever 14, thereby permitting the said bell-crank lever to turn on its pivot by action of its spring 21, which causes the arm 15 of the said bell-crank lever to engage the lug 9 on the belt-shifter 6, and thus move the driving belt off the driving pulleys and onto the loose pulley 5. This longitudinal movement of the slide bar 19 also causes the stop or holding pin 54 to move away from the brake-applying lever 50, permitting this lever to be turned on its pivot by its spring 53 which causes the screw 52 to engage the free end of the brake lever 45, and thereby apply the brake shoe 49 to the tight pulley with which it is aligned, thereby stopping the knitting machine.

50 Figs. 4 to 7 inclusive show an adaptation of the invention applied to a "Brinton" machine, the main frame of which is indicated at 1a, having a main shaft 2a on which is mounted the usual high-speed tight pulley 3a and the usual low speed and loose pulleys 4 and 5 respectively, which are of the same diameter as the pulley 3a.

55 In this type of machine, the belt-shifting yoke 6a is secured to a shift rod 7a which is slidably mounted in suitable bearings on the frame 1a for moving the belt from the high speed to the low speed pulley. This operation is effected at the proper time from and by suitable cams secured on a drum 60, through mechanism (not shown) forming no part of the present invention. Movement of the belt-shifting rod 7a and the yoke 6a to effect a movement of the belt from either the high speed or low speed pulleys to the loose pulley, and vice versa, is controlled by a toggle 61 which when the levers thereof are longitudinally extended moves the belt to either of the power pulleys and when collapsed permits the movement of the belt to the loose pulley by a spring (not shown) which is regular equipment in this machine. Collapse of the toggle for shifting the belt to stop the machine when the knitting of an article has been finished is controlled by the drum 60 through a lever 62. The raising of the end of the lever 62 adjacent the drum lowers the opposite end thereof to collapse the toggle 61, whereupon the spring which controls the sliding movement of the shift bar 7a effects the shifting of the belt to the loose pulley.

60 My invention relative to this type of machine comprises a casing 11a which is secured to the machine frame 1a. Horizontally and slidably mounted in the casing 11a is a slide

bar 19a which is connected by a link 63 to a vertically slidable trip bar 64, the upper end of which is provided with an adjustable abutment in the form of a screw 65 which is adapted to engage the drum end of the lever 62 and thereby collapse the toggle 61 for effecting the stopping of the machine.

A spring 24a is adapted to effect the longitudinal sliding movement of the bar 19a in an operative direction, and the bar 19a is adapted to be moved in the opposite resetting direction by a lever 27a pivoted at 28a to the casing 11a. One end of the lever 27a is adapted to engage a pin 29a which extends laterally from the slide bar 19a, and to the opposite end of the lever 27a is connected an operating rod 31a.

A locking lever 33a is pivoted at 34a to the casing, and is provided with a slot 35a and a notch 36a in which a locking pin 37a, extending laterally from the slide bar 19a, is adapted to operate. The locking lever 33a is provided with a shouldered end 38a adapted to be engaged by a latch 39a which is pivoted at 40a to the casing 11a. A spring 41a holds the latch 40a in operative engagement with the locking lever 33a.

The latch 39a is engaged by a pin or lever arm 42a which extends laterally from a shaft 43a rotatably mounted in the casing 11a and provided at its outer end with an arm 70. The arm 70, shaft 43a and arm 42a form a bell-crank lever for operating the latch 39a. The arm 70 is adapted to be engaged by an arm 71 secured to one end of a short vertical shaft 72 rotatably mounted in a bearing 73 on the casing 11a. The upper end of the short shaft 72 is operatively connected to the rotatable stop motion trip rod 44a of the machine.

The casing 11a has an extended bracket 47a on which is pivotally mounted at 46a a brake lever 45a. The brake lever 45a has an eccentrically located pin 48a on which is pivotally mounted a brake shoe 49a. The brake shoe is adapted to engage the tight pulley 3a on the main drive shaft 2a of the machine. The brake lever 45a is adapted to be engaged by a threaded stud 52a carried by the slide bar 19a.

In the operation of this form of the invention, when a thread becomes slack or broken the stop motion trip rod 44a is partially rotated, which rotates the short shaft 72 causing the arms 71 thereon to engage the arm 70 of the bell-crank lever 70-43a-42a. The arm 42a of the said bell-crank lever bears down on one end of the latch 39a raising the opposite end against the action of the spring 41a and releasing the locking lever 33a. When released, the locking lever is swung on its pivot by the pin 37a moving out of the notch 36a into the slot 35a, which assumes a position parallel to the slide bar 19a, under the

influence of the spring 24a which effects longitudinal movement of the slide bar 19a.

As the slide bar 19a is moved horizontally by the spring 24a the stud 52a engages the end of the brake lever 45a, swinging the same in its pivot 46a and thereby applying the brake 49a to the pulley 3a. Simultaneously therewith the link 63 moves the vertical slide bar 64 upwardly, the stud 65 engaging and raising the drum end of the lever 62, which swings about its pivot depressing the toggle end thereof which engages the toggle 61 and collapses the same, whereupon the spring (not shown) which controls the longitudinal movement of the shift rod 7a causes the said shift rod to be moved longitudinally, causing the belt shifting yoke 6a to move accordingly and consequently moving the drive belt from the tight to the loose pulley of the machine.

To reset the device the rod 31a is operated to turn the lever 27a on its pivot, whereupon the said lever engages the pin 29a on the slide bar 19a and moves the same rearwardly. The rearward movement of the slide bar 19a, through the link 63, lowers the vertical trip bar 64 and thereby releases the toggle operating lever 62, and at the same time the pin 37a moves into the notch 36a in the locking lever 33a, turning the same on its pivot until the end 38a thereof is engaged and held by the latch 39a. This rearward movement of the slide bar 19a releases the brake lever 45a and places the spring 24a under tension for subsequent operation of the slide bar 19a when the trip rod 44a is again rotated by the breaking or other irregular condition in the thread.

Figs. 8, 9 and 10 illustrate another form of the invention as applied to a machine of the "Wildman" type, and comprises a casing 11b adapted to be secured to the frame of the machine, and having a slide bar 19b mounted for horizontal movement therein. A spring 24b is adapted to move the slide bar in a direction to apply the brake 49b to the drive pulley 3b of the machine. Movement of the slide bar in this direction is restrained by a locking lever 33b pivoted at 34b to the casing 11b, and having a notch 36b at the vertex of the divergent sides of a slot or mouth 35b formed in the locking lever 33b. The notch 36b is adapted to receive and hold a pin 37b which extends laterally from and is rigidly secured in the slide bar 19b.

The outer end 38b of the locking lever 33b is engaged and held in its locking position by one end of a latch 39b pivoted at 40b to the casing 11b. A spring 41b maintains the latch 39b in its lever holding position. The opposite end of the latch 39b is adapted to be engaged by an arm or pin 42b projecting from a vertically disposed rotatable shaft 43b, which is operatively connected to the stop motion trip rod 44b on the machine.

The brake shoe 49b is pivotally mounted on a pin 48b which is eccentrically located on

and with respect to the pivot 46b of the brake lever 45b. The brake lever pivot 46b is carried by a bracket 47b secured to the frame 1b of the machine. On one end of the slide bar 19b is a bracket 50b which carries a stud 52b adapted to engage the brake lever 45b and thereby apply the brake 49b to the drive pulley 3b of the machine, when the latch 39b is tripped by rotary action of the trip rod 44b, which releases the locking lever 33b permitting the same to turn on its pivot and thereby release the pin 37b from the retaining notch 36b in the locking lever 33b, whereupon the spring 24b will move the slide bar 19b longitudinally to apply the brake.

The slide bar 19b is moved in the opposite or resetting direction by a lever 27b pivoted at 28b to the casing 11b. One end of the lever 27b engages a pin 30b which extends laterally from the slide bar 19b, and the opposite end of the lever has an opening 75 through which a setting rod 31b passes. On one end of the rod 31b is a collar 76 which is adapted to engage the lever 27b when the rod 31b is moved longitudinally forward. The opposite end of the rod 31b is pivotally connected to a setting lever 32b which is pivoted at any convenient place on a rigid part of the machine. A spring 77 maintains the resetting levers 27b, 32b and the resetting rod 31b in an inoperative position.

When the slide bar 31b moves to apply the brake 49b, the pin 30b therein engages the lever 27b and turns it on its pivot, the lower end of said lever moving along the rod 31b into contact with the collar 76. By pulling the lever 32b, the 31b is moved longitudinally forward, the collar 76 engaging the lower end of the lever 27b rocks the lever 27b on its pivot and consequently moves the slide bar 19b rearwardly to release the brake 49b. In the rearward movement of the slide bar 19b, the pin 37b thereon enters the mouth 35b of the locking lever 33b and upon striking the edge 78 of said mouth 35b turns the lever 33b on its pivot, the notch 36b engaging and holding the pin 37b and the forward end 38b of the lever 33b engaging the latch 39b which thereafter holds the lever 33b in its locking position.

The belt shifting yoke 6b of this type of machine is carried by a lever 80 which is pivoted at 81 to a bracket 82 secured to the frame 1b of the machine. On the pivot 81 is also pivotally mounted a lever 83, the upper end of which is provided with a bearing 83a for a shaft 84. On one end of the shaft 84 is secured a handle 85 and a lever 86. The lever 86 is provided with a slot 87 having a notch 88. A pin 89 on the lever 80 is located in the notch 89, and holds the lever 80 and the belt shifting yoke 6b in position to maintain the belt on the drive pulley 3b against the action of a spring 90.

65 The drive belt is shifted from one drive

pulley 3b to another drive pulley 4b for driving the machine at either high or low speed by means of a suitable cam (not shown) forming no part of the present invention.

The drive belt is shifted from either of the drive pulleys to the loose pulley 5b, when the slide bar 19b is moved longitudinally to apply the brake, by a cam 91, on the bracket 50b, engaging a lever 92 secured to a short shaft 83 rotatably mounted in a bearing 94 formed in the bracket 47b. A lever 95 is also secured to the short shaft 93, and is adapted to engage a lever 96 secured to the rear end of the shaft 84 carried by the lever 83.

In operation, as the slide bar 19b moves forward to apply the brake the cam 91 engages the lever 92 which turns the shaft 93 and lever 95 carried thereby. The lever 95 engages the lever 96 which turns the shaft 84 and the lever 86 carried thereby, which releases the pin 89 from the notch 88. The spring 90 then turns the lever 80 on its pivot and the belt shifting yoke 6b moves the belt from the drive pulley, on which it happens to be running at the time, to the loose pulley 5b.

I claim:

1. With a knitting machine having a driving pulley, a stop motion, and an axially rotatable trip rod operated by said stop motion; the combination of a readily attachable unit comprising a frame adapted to be rigidly secured to the knitting machine, a brake-carrying arm pivoted to said frame, a brake shoe pivotally mounted on said brake arm and adapted to engage said driving pulley, an operating element for said arm, means for moving said operating element to apply said brake, restraining means for said operating element, a supplementary axially rotatable trip rod carried by said frame and universally connected to the axially rotatable trip rod of said stop motion, and means operated directly from and by rotation of said supplementary trip rod for releasing said restraining means.

2. With a knitting machine having a driving pulley, a stop motion, and an axially rotatable trip rod operated by said stop motion; the combination of a readily attachable unit comprising a frame adapted to be rigidly secured to the knitting machine, a brake-carrying arm pivoted to said frame, a brake shoe pivotally mounted on said brake arm and adapted to engage said driving pulley, an operating element for said brake arm, means for moving said operating element to apply said brake, restraining means for said operating element, supplementary axially rotatable trip rod carried by said frame and universally connected to the axially rotatable trip rod of said stop motion, means operated directly from and by rotation of said supplementary trip rod for releasing said restraining means, and means for resetting said brake operating element.

3. With a knitting machine having a driving pulley, a stop motion, an idler pulley, means for shifting a drive belt from one to the other of said pulleys, and an axially rotatable trip rod operated by said stop motion; the combination of a readily attachable unit comprising a frame adapted to be rigidly secured to the knitting machine, a brake-carrying arm pivoted to said frame, a brake shoe pivotally mounted on said brake arm and adapted to engage said driving pulley, an operating element for said brake arm, means for moving said operating element to apply said brake, restraining means for said 10 operating element, a supplementary axially rotatable trip rod carried by said frame and universally connected to the axially rotatable trip rod of said stop motion, means operated directly from and by rotation of said supplementary trip rod for releasing said restraining means, and means operated by said brake operating element for effecting operation of said belt shifting mechanism to shift the drive belt from the driving pulley to the idler pulley.

4. With a knitting machine having a driving pulley, a stop motion, an idler pulley, means for shifting a drive belt from one to the other of said pulleys, and an axially rotatable trip rod operated by said stop motion; the combination of a readily attachable unit comprising a frame adapted to be rigidly secured to the knitting machine, a brake-carrying arm pivoted to said frame, a brake shoe pivotally mounted on said brake arm and adapted to engage said driving pulley, an operating element for said brake arm, means for moving said operating element to apply said brake, restraining means for said operating element, a supplementary axially rotatable trip rod carried by said frame and universally connected to the axially rotatable trip rod of said stop motion, means operated directly from and by rotation of said supplementary trip rod for releasing said restraining means, means operated by said brake operating element for effecting operation of said belt shifting mechanism to shift the drive belt from the driving pulley to the idler pulley, and means for resetting said brake operating element for subsequent release effected by said trip rod.

5. With a knitting machine having a drive pulley, an idler pulley, a stop motion, and an axially rotatable trip rod operable by said stop motion; the combination of a readily attachable unit comprising a frame adapted to be rigidly secured to the knitting machine, a brake-carrying arm pivoted to said frame, a brake shoe pivotally mounted on said brake arm and adapted to engage said drive pulley, a slide bar for controlling the operation of said brake arm, resilient means for sliding said bar longitudinally, means for locking said slide bar against said longitudinal move-

ment, a supplementary axially rotatable trip rod carried by said frame and universally connected to the axially rotatable trip rod of said stop motion, and means operable directly from and by rotation of said supplementary trip rod for releasing said bar from said locking means.

6. With a knitting machine having a drive pulley, an idler pulley, a stop motion, and an axially rotatable trip rod operable by said stop motion; the combination of a readily attachable unit comprising a frame adapted to be rigidly secured to the knitting machine, a brake-carrying arm pivoted to said frame, a brake shoe pivotally mounted on said brake arm and adapted to engage said drive pulley, a bar slidably mounted in said frame for controlling the operation of said brake arm, resilient means for sliding said bar longitudinally to effect the operation of said brake, a lever pivoted to said frame and engaging a projection on said bar for locking said slide bar against said longitudinal movement, a supplementary axially rotatable trip rod carried by said frame and universally connected to the axially rotatable trip rod of said stop motion, and means operable directly from and by rotation of said supplementary trip rod for releasing said bar from said locking lever.

7. With a knitting machine having a drive pulley, an idler pulley, a stop motion, and an axially rotatable trip rod operable by said stop motion; the combination of a readily attachable unit comprising a frame adapted to be rigidly secured to the knitting machine, a brake-carrying arm pivoted to said frame, a brake shoe pivotally mounted on said brake arm and adapted to engage said drive pulley, a bar slidably mounted in said frame for controlling the operation of said brake arm, a resilient means for sliding said bar longitudinally to effect the operation of said brake, a lever pivoted to said frame and engaging a projection on said bar for locking said slide bar against said longitudinal movement, a latch pivoted to said frame and adapted to engage said locking lever, a supplementary axially rotatable trip rod carried by said frame and universally connected to the axially rotatable trip rod of said stop motion, and means on and operable by rotation of said supplementary trip rod for releasing said locking lever from said latch.

8. With a knitting machine having a drive pulley, an idler pulley, a stop motion, and an axially rotatable trip rod operable by said stop motion; the combination of a readily attachable unit comprising a frame adapted to be rigidly secured to the knitting machine, a brake-carrying arm pivoted to said frame, a brake shoe pivotally mounted on said brake arm and adapted to engage said drive pulley, a bar slidably mounted in said frame for controlling the operation of said brake arm,

- a resilient means for sliding said bar longitudinally to effect the operation of said brake, a lever pivoted to said frame and engaging a projection on said bar for locking said slide bar against said longitudinal movement, a latch pivoted to said frame and adapted to engage said locking lever, means for resiliently maintaining said latch in its lever holding position, a supplementary axially rotatable trip rod carried by said frame and universally connected to the axially rotatable trip rod of said stop motion, and means on and operable by rotation of said trip rod for releasing said latch from said locking lever.
15. 9. With a knitting machine having a drive pulley, an idler pulley, a stop motion, and an axially rotatable trip rod operable by said stop motion; the combination of a readily attachable unit comprising a frame adapted to be rigidly secured to the knitting machine, a brake-carrying arm pivoted to said frame, a brake shoe pivotally mounted on said brake arm and adapted to engage said drive pulley, a bar slidably mounted in said frame for controlling the operation of said brake arm, a resilient means for sliding said bar longitudinally to effect the operation of said brake, a lever pivoted to said frame and engaging a projection on said bar for locking said slide bar against said longitudinal movement, a latch pivoted to said frame and adapted to engage said locking lever, means for resiliently maintaining said latch in its lever holding position, a supplementary axially rotatable trip rod carried by said frame and universally connected to the axially rotatable trip rod of said stop motion, and an arm on said supplementary trip rod adapted to engage said latch for releasing said locking lever therefrom.
20. 10. With a knitting machine having a drive pulley, an idler pulley, a stop motion, and an axially rotatable trip rod operable by said stop motion; the combination of a readily attachable unit comprising a frame adapted to be rigidly secured to the knitting machine, a brake-carrying arm pivoted to said frame, a brake shoe pivotally mounted on said brake arm and adapted to engage said drive pulley, a bar slidably mounted in said frame for controlling the operation of said brake arm, resilient means for sliding said bar longitudinally to effect the operation of said brake, a lever pivoted to said frame and having a notch formed therein, a projection on said slide adapted to be engaged by the notch in said lever for restraining said bar against said longitudinal movement, a latch adapted to hold said lever in its bar locking position, a supplementary axially rotatable trip rod carried by said frame and universally connected to the axially rotatable trip rod of said stop motion, and means on and operable by rotation of said supplementary trip rod for releasing said latch.
25. 11. With a knitting machine having a driving pulley, an idler pulley, means for shifting a drive belt from one to the other of said pulleys, a stop motion, and an axially rotatable trip rod operated by said stop motion; the combination of a readily attachable unit comprising a frame adapted to be rigidly secured to the knitting machine, a brake-carrying arm pivoted to said frame, a brake shoe pivotally mounted on said brake arm and adapted to engage said driving pulley, a slide bar controlling the operation of said brake arm, means for moving said slide bar longitudinally to effect the operation of said brake, a locking lever adapted to engage said slide bar and restrain it against said longitudinal movement, a supplementary axially rotatable trip rod carried by said frame and universally connected to the axially rotatable trip rod of said stop motion, means operable directly from and by rotation of said supplementary trip rod for releasing said locking lever from said slide bar; and means operable by said slide bar for effecting the operation of said belt shifting means for moving said belt from the driving to the idler pulley of the machine simultaneous with the operation of said brake.
